(57) **CLAIM**

The ornamental design for a golf tool with overmolding, substantially as shown.

DESCRIPTION

FIG. 1 is a front elevational view of a golf tool with overmolding, in accordance with the present invention; FIG. 2 is a rear elevational view thereof;

FIG. 3 is a top view thereof;

FIG. 4 is a bottom view thereof;

FIG. 5 is a right side view thereof;

FIG. 6 is a left side view thereof; and,

FIG. 7 is a cross sectional view taken on line 7—7 of FIG. 2.

The broken lines of FIGS. 1, 2, 3, 4, 6, and 7 are for illustration only and form no part of the claimed design.
